UNITED STATES PATENT OFFICE.

THOMAS E. VAN METRE AND JAMES S. CURRIER, OF NEWPORT, RHODE ISLAND,
ASSIGNORS TO THE GOVERNMENT OF THE UNITED STATES.

TORPEDO.

Application filed May 17, 1922. Serial No. 561,701.

To all whom it may concern:

Be it known that we, THOMAS E. VAN METRE and JAMES S. CURRIER, both citizens of the United States, residing at Newport, Rhode Island, respectively, have invented

new and useful Improvements in Torpedoes, of which the following is a specification.

This invention relates to improvements in torpedoes and more particularly to improvements in the practice head.

To enable one to more fully understand the invention it may be briefly stated that the standard Navy torpedo may be said to be divided into three parts, the after-body 15 containing the engine and steering mechanism, the central body containing the air flask and fuel chambers and the forward end or war head.

Prior to the acceptance of the torpedo 20 after its construction, it is put through a number of severe tests during which a practice head of substantially the same size and shape is substituted for the war head. These test runs are not always successful and it 25 frequently happens that a torpedo leaves the range or the engine or steering mechanism are defective causing the torpedo to sink to the bottom of the range during trial and it is difficult under such circumstances to locate 30 the torpedo and recover the same whereby recourse may be made and further tests carried out.

The present invention, therefore, is directed to an improved practice head provided with means adapted to insure a relative positive buoyancy of the complete torpedo and bring it to the surface if for any reason it goes below a predetermined depth.

One of the objects of the present invention 40 is to provide a simple and practical mechanism of the above general character which will be reliable and efficient in use and operation.

A further object is to provide an improved 45 practice head with an inexpensive assembly which may be easily and quickly installed in practice heads now in general use without material modification.

A further object is to provide a mechanism 50 of the last above mentioned character which will not function until after a predetermined delay which time element allows the torpedo to come to its proper depth setting.

A further object is to provide a mechanism of the last above mentioned character with steering means cooperating with the practice head to cause an upward deflection thereof.

A further object is to provide a mechanism of the above character which will operate after a predetermined time in cases where the water is not sufficiently deep to cause an operation of the mechanism hydrostatically.

Other objects will be in part obvious and in part hereinafter pointed out in connection with the accompanying sheets of drawings illustrating such parts of the practice head as are necessary to understand the invention.

In these drawings wherein similar reference characters are denoted by corresponding parts,

Figure 1 is a longitudinal, central, sectional view of the complete head, and,

Figure 2 is a vertical central sectional view of the actuating mechanism.

Referring now to the drawings in detail and more particularly to Figure 1, the head shell 5 is of the usual standard type provided with strengthening ribs 6 and a nose piece not shown to facilitate handling and recovery of the torpedo. The usual standard torch case 8 and depth and rolling register mechanism 9 are indicated in outline but have no special part or relation in the present invention. The rear end of the practice head is provided with a joint ring 10, a bulkhead 11 and bulkhead ring 12 with suitable gaskets 14 of substantially the usual construction only slightly reenforced for the purpose of more effectively resisting the internal gas pressure developed within the practice head by the mechanism hereinafter described. This practice head is filled with water through an inlet plug 16 at the top which water may be drawn off through an outlet plug 17 at the bottom. A water outlet valve 18 is normally held in closed position by spring 20 against its seat 21, ballast 22 is provided at the forward end of the head as may be necessary. The mechanism shown in Figure 2 for effecting the change of buoyancy in the torpedo and also cause an upward deflection of the torpedo if it is still in motion comprises broadly a bow rudder 23 shown in operative raised position in

dotted lines and a gas generating mechanism including a chemical 24 within the container 25 which, under certain conditions, is adapted to be mixed with water 26 within the receptacle 27. The construction of this mechanism may be more clearly described in conjunction with a statement of the operation which is as follows:—

When the torpedo is launched, sea water 10 enters through the chute 28 and passes through openings 30 to a delay chamber 31. The openings 30 are preferably made small whereby there will be a certain delay before the mechanism can operate thus allowing the 15 torpedo time to make a deep initial dive without operating the mechanism. After the delay chamber is once filled any deviation of the torpedo below its normal running depth will increase the hydrostatic pressure 20 upon a diaphragm 32 and if the set or 40 foot depth is approached the pressure on this diaphragm is sufficiently great to overcome the pressure of spring 33 thereby allowing a piston 34 to be forced downwardly 25 by the hydrostatic pressure of the water within the delay chamber 31 causing the ball release mechanism 35 to move downwardly also thereby pushing a cutter 36 ahead of it.

Such downward movement of the piston 30 34 will cause the ball release 35 to move downwardly also to release a ball 38 whereby the sea water pressure under the bow rudder 23 will cause the latter to rise to the dotted line position and force the ball 38 35 rearwardly. The bow rudder now being released pivots about its hinge 40 and swings upwardly until stopped at the dotted line position by means of the links 41 and 42, the shock of the opening being absorbed by 40 a checking spring 43. The bow rudder in this position immediately gives the torpedo an "up-rudder" and it comes to the surface.

At the same time the bow rudder is being released the cutting plunger 36 is cutting 45 the seal 44 in the water chamber 27 and the water 26 flows into chemical tank 25 containing a mixture of certain chemicals adapted to evolve large quantities of gas when mixed with water, for instance, equal 50 parts by weight of tartaric acid and sodium bicarbonate will answer the purpose. This results in the rapid generation of a large volume of gas, the pressure of which is sufficient to blow off the bottom cover 45 and 55 release the entire contents 24 of the container 25 which drop into the cylinder 46 where the chemical action is continued in greater volume by the admixture of water from the head, this water having free access 60 to the gas generating cylinder through openings 47 and small holes 48 in the side. This cylinder prevents the ejection of the unused chemicals through the water outlet valve 18 because if deposited in the open head 65 there would be a possibility of them being

ejected before the water had sufficient time to unite with them to form the desired quantity of gas.

The gas pressure generated forces the valve 18 open by overcoming the pressure of spring 20 and the water is blown out through the holes at the bottom thus causing the head to develop a positive buoyancy.

There is provided a means for operating the gas generating mechanism in case the 75 torpedo should sink at any point during its run in water insufficient to operate the depth spring 33. This means comprises a soluble washer 50 in the delay chamber 31 upon which the water begins to act as soon as the 80 torpedo is launched. After a predetermined period of time release spring 51 operates upon the cutting plunger 36 to carry the same downwardly thereby cutting the seal 44 and releasing the water within the container 27 after which the action is the same as that above described. In assembling the present mechanism, the chemical tank 25 is made up with the container 27 ready for use. Prior to making a trial shot with the torpedo water is put into the container 27 and the casing carrying the time and depth features is then screwed into the tank. The two units are then placed in a flange 52 and secured in place by screws 53. The bow rudder 23 and plate 54 together with the ball spring and links associated therewith are secured in place by any desired means such as a bayonet joint indicated by flange 55. A set screw may be provided, if desired, to 100 prevent lateral movement.

From the above it is believed that the construction and operation will be clear to those familiar with the subject and a further statement thereof is unnecessary.

The invention is of simple and practical construction, reliable and efficient in use and operation and may be easily and quickly installed.

Without further analysis, the foregoing 110 will so fully reveal the gist of this invention that others can by applying current knowledge readily adapt it for various applications without omitting certain features that, from the standpoint of the prior art, fairly 115 constitute essential characteristics of the generic or specific aspects of this invention and, therefore, such adaptations should and are intended to be comprehended within the meaning and range of equivalency of the 120 following claims:

1. In a practice head for torpedoes, in combination, a receptacle adapted to contain gas forming materials, guiding means associated with the outer shell of the head and means for simultaneously actuating said guiding means and admitting water to said gas forming material whereby said torpedo is caused to come to the surface if it sinks beyond a predetermined depth.

2. In a practice head for torpedoes, in combination, a receptacle adapted to contain gas forming materials, a water chamber adjacent thereto, a bow rudder and means for simultaneously releasing said bow rudder and admitting the water from said receptacle to said gas forming material if the torpedo sinks to a predetermined depth.
3. In a practice head for torpedoes, in combination, steering means associated with the exterior of the practice head which, when actuated, is adapted to cause an upward deflection of the torpedo, hydrostatically actuated means for releasing said steering means when the torpedo reaches a predetermined depth and a receptacle adapted to contain a gas forming material within the practice head to which water is adapted to be admitted with the actuation of said steering means.
4. In a practice head for torpedoes, in combination, steering means associated with the exterior of the practice head which, when actuated, is adapted to cause an upward deflection of the torpedo, hydrostatically actuated means for releasing said steer-
- ing means when the torpedo reaches a predetermined depth, a receptacle containing gas forming material, an auxiliary receptacle containing water adjacent thereto, means for admitting the water to the gas forming material simultaneously with the actuation of said steering mechanism including said hydrostatically actuated means which releases the steering means and establishes communication between the water chamber and the receptacle.
5. In a practice head for torpedoes, in combination, a pivotally mounted bow rudder associated with the outer shell of said head, means for releasing said bow rudder, means for taking up the shock as said bow rudder swings into operative position, a chamber containing gas forming material, a second chamber containing water associated therewith and means for establishing communication between said chambers when said bow rudder is released.

Signed at Newport, Rhode Island, this 27th day of March, 1922.

THOMAS E. VAN METRE.
JAMES S. CURRIER.
